DESIGN FOR A SLIP

Albert A. Horwitch, Chicago, Ill.

Application October 16, 1941, Serial No. 103,782

Term of patent 7 years

To all whom it may concern:

Be it known that I, Albert A. Horwitch, a citizen of the United States, residing at Chicago, in the county of Cook and State of Illinois, have invented a new, original, and ornamental Design for a Slip, of which the following is a specification, reference being made to the accompanying drawing, forming a part thereof in which—

Fig. 1 is a front elevational view of a slip embodying my new design; and

Fig. 2 is a rear elevational view of the same.

I claim:
The ornamental design for a slip, substantially as shown.

ALBERT A. HORWITCH.
